UNITED STATES PATENT OFFICE

114,016

DESIGN FOR AN OVERALL ENSEMBLE

William Friedman, New York, N. Y.

Application February 21, 1939, Serial No. 83,138

Term of patent 3½ years

To all whom it may concern:

Be it known that I, William Friedman, a citizen of the United States of America, residing in 229 West 36th Street, county of New York and State of New York, have invented a new, original, and ornamental Design for an Overall Ensemble, of which the following is a specification, reference being had to the accompanying drawing, forming part thereof.

Fig. 1 is a front view of an overall ensemble showing my new design.

Fig. 2 is a fragmentary rear view of the upper portion of Fig. 1.

Fig. 3 is a front view of the overall ensemble without the coat portion.

Fig. 4 is a rear view of Fig. 3.

I claim:

The ornamental design for an overall ensemble, substantially as shown.

WILLIAM FRIEDMAN.
